No. 741,096.

PATENTED OCT. 13, 1903.

J. B. BEAM.

OIL CAN.

APPLICATION FILED APR. 6, 1903.

NO MODEL.

UNITED STATES PATENT OFFICE.

JACOB B. BEAM, OF BIGRUN, PENNSYLVANIA.

OIL-CAN.

SPECIFICATION forming part of Letters Patent No. 741,096, dated October 13, 1903.

Application filed April 6, 1903. Serial No. 151,329. (No model.)

To all whom it may concern:

Be it known that I, JACOB B. BEAM, a citizen of the United States, residing at Bigrun, in the county of Jefferson and State of Pennsylvania, have invented certain new and useful Improvements in Oil-Cans, of which the following is a specification.

My invention relates to that class of oil-cans in which pumping apparatus is employed for forcing oil from the spout; and the object of my invention is to equip an oil-can with improved pumping apparatus which may be easily applied to or removed from the can, may be easily operated, and which while simple in construction is efficient in operation.

In carrying out my invention I provide an oil-can of ordinary construction with a removable bottom, to which is attached a cylinder connected with the interior of the can by a valved passage and in which operates a valved piston, which is reciprocated by a tube which telescopes with the spout of the can and moves up and down therein. The tube is reciprocated by means of a bell-crank lever pivoted on a bracket within the can and connected by means of jointed rods or links with a hand-lever located within the handle of the can and pressed in one direction by a spring, the arrangement being such that the can may be held by one hand in the usual way and operated by the same hand to expel the oil, while the other hand of the user may be unemployed or employed in some other way.

In the accompanying drawings, Figure 1 is a view, partly in side elevation and partly in section, of an oil-can embodying my improvements. Fig. 2 is a view, on an enlarged scale, of the lower part of the can with parts broken away to illustrate the mechanism contained within the can. Figs. 3 and 4 are detail views of the cage employed for confining the ball-valves.

The main body of the can A is of the usual construction and has a spout B of the ordinary kind. The bottom of the can is formed with a central opening around which is a depending screw-threaded flange a, adapted to engage a screw-threaded flange c on a cap C, that closes the bottom opening. A rubber gasket a' is preferably interposed between the upper end of the flange c and the bottom of the can in order to form a tight joint. To

the cap C is attached the cylinder D of the pumping apparatus. The interior of the cylinder communicates with the interior of the can by means of a valved passage E. The pipe e of this passage extends from an opening e' in the side of the cylinder near its lower end to the central portion of the cylinder, where it is provided with a cage F, containing a ball-valve f. The cage F is preferably formed in the manner indicated in Figs. 3 and 4, being stamped from sheet metal with the circular central portion f' and four radial arms f''. The arms are bent, and the central portion is made concavo-convex, in the manner indicated in Fig. 4, the outer ends of the arms being attached to the inner end of the tube e in the manner indicated in Fig. 2, thus leaving openings x, by which communication may be established between the interior of the cylinder and the passage E. The inner end of the tube e is properly formed with a valve-seat to accommodate the ball-valve. The piston G is fitted to reciprocate easily but tightly in the cylinder D. It is attached to a tube H, which latter telescopes at h with another tube or tubular guide I, arranged within the spout B, extending nearly to the upper end thereof and being braced and secured at its lower end by rods J, attached to the can. The tube H is adapted to reciprocate longitudinally in the tube I. The piston is provided with a valve-chamber K, containing a cage L, similar to the cage F, within which is a ball-valve M, fitting a valve-seat arranged over an opening m in the piston. When the ball-valve falls or is in its lowermost position, the opening between the cylinder and the tube H is closed; but when the ball-valve rises, as it does when the piston descends, communication is established between the interior of the cylinder and the tube H.

By the arrangement described when the piston rises the valve f opens and oil may be drawn from the interior of the can into the interior of the cylinder D, the valve M at this time being closed. When the piston descends, the valve f closes, while the valve M opens, and oil may pass through the opening m into the tube H, and from the tube H oil passes into the tube I and then out through the spout. In order to conveniently recipro-

cate the piston, I employ mechanism arranged within the handle N of the oil-can and connected with the piston in such manner as to operate it easily by an easy movement of the fingers. The tube H is provided with laterally-projecting studs or arms n, which are embraced by the bifurcated ends o of a bell-crank lever O, pivoted to a bracket P within the can and having its shorter arm o' slotted at o² and connected with a rod Q, that reciprocates through a stuffing-box R, and is connected by means of a link S to a lever T, the main portion of which is disposed vertically, but which has a lower curved end t, pivoted to a bracket t', attached to the outside of the can. The handle N is preferably curved in the manner indicated, and to it is attached a leaf-spring U, which at its outer free end bears against the lever T and tends to move the bell-crank lever in such direction as to lift the piston.

In operation the hand which grasps the handle may easily draw the lever T outward in such manner as to depress the piston, and thus force oil out through the nozzle. When the fingers are released from the lever T, the spring U acts to lift the piston, and thus draw more oil into the cylinder D. By repeatedly operating the lever T in this way the cylinder D may be filled, and oil may be forced out through the nozzle.

Among the advantages of the construction described are that the pumping apparatus may be easily attached to and taken from the oil-can. By removing the cap C the cylinder and parts attached thereto may be easily taken out, and I may employ a removable plate V, carrying the bracket P, stuffing-box R, and the bracket t'. By removing the plate the lever O, lever T, and parts connected therewith may be detached.

I claim as my invention—

1. The combination of an oil-can having an opening in the bottom and a spout at the top, a guide-tube within the spout, a tubular piston-rod telescoping with the guide and detachable therefrom, a cap detachably secured to the can and covering the opening in the bottom thereof, a pump-cylinder secured to the cap and removable therewith from the

can, a piston attached to the piston-rod and removable therewith through the opening in the bottom of the can, and valved passages for admitting oil to and discharging it from the cylinder.

55

2. The combination of an oil-can having an opening in the bottom and formed with a depending screw-flange around the opening, a cap having a vertical screw-flange engaging the flange on the bottom of the can and covering the opening therein, a pump-cylinder attached to the cap removable therewith from the can and having an annular surrounding space within the cap, a valved passage connecting such annular space in the cap with the interior of the cylinder, a piston reciprocating in the cylinder, a valved passage leading from the cylinder through the piston, and means for reciprocating the piston.

60

3. The combination of an oil-can having a discharge-nozzle, a pump within the can, valved passages connecting the pump with the interior of the can and with the nozzle, a bell-crank lever arranged inside the can and having a bifurcated end loosely and detachably connected with the piston of the pump, a handle for the oil-can, an oscillating lever arranged within the handle, and connections between the oscillating lever and the bell-crank lever.

65

4. The combination of an oil-can having a discharge-nozzle, a pump within the can, valved passages connecting the pump with the interior of the can and with the nozzle, a bell-crank lever arranged inside the can, a plate removably connected with the can to which said bell-crank lever is pivoted, detachable connections between the bell-crank lever and the piston-rod of the pump, a handle for the oil-can, an oscillating lever arranged within the handle and pivoted to said removable plate, and connections between said oscillating lever and said bell-crank lever.

70

In testimony whereof I have hereunto subscribed my name.
